United States Patent Office

Des. 198,304
Patented May 26, 1964

198,304

HANDLE OR SIMILAR ARTICLE

Frederick Gordon Mackay and Gerald W. Schmidt, Tarzana, Calif., assignors to Price-Pfister Brass Mfg. Co., Los Angeles, Calif., a corporation of California

Filed Apr. 8, 1963, Ser. No. 74,354

Term of patent 14 years

(Cl. D91—3)

FIG. 1.

FIG. 2.

FIG. 3.

FIG. 4.

FIG. 2 is a side elevational view thereof; and

FIGS. 3 and 4 are top and bottom plan views thereof.

We claim:

The ornamental design for a handle or similar article, substantially as shown.
